UNITED STATES PATENT OFFICE.

WILLIAM O'HERIN, OF PARSONS, KANSAS.

ATMOSPHERIC BRAKE.

SPECIFICATION forming part of Letters Patent No. 312,155, dated February 10, 1885.

Application filed September 20, 1884. (No model.)

To all whom it may concern:

Be it known that I, WILLIAM O'HERIN, of Parsons, Kansas, have made a new and useful Improvement in Atmospheric Brakes, of 5 which the following is a full, clear, and exact description, reference being had to the annexed drawings, making part of this specification, in which—

Figure 1 is a view in perspective of the improved valve; Fig. 2, a side elevation of that portion of an atmospheric car-brake mechanism with which the improvement is immediately connected; Fig. 3, a longitudinal section of the valve opened, and Fig. 4 a longitudinal section of the valve closed.

The same letters of reference denote the same parts.

In connection with that portion of the mechanism of an atmospheric car-brake which is 20 used to connect the cars—namely, the flexible tubes which project from opposing cars and are coupled together beneath the cars—it has been customary to employ a cut-off valve at or in the vicinity of the inner end 25 of each of the flexible tubes, by means of which the operator can cut off the passage of the air through the main air-tubes beneath the car. Prior to the adoption of these cut-off valves the coupling was provided with a 30 peculiar system of valves, whose function was to close the ends, respectively, of the tubes, and prevent the escape of the air whenever the tubes were uncoupled; but the introduction of the cut-off valves obviated the 35 need of a valve in the coupling, the practice now being to close the cut-off valves and then uncouple the tubes. This difficulty, however, has remained: while the closing 40 of the cut-off valve serves to prevent the passage of the air between the main tube beneath the car and the flexible tube at the end of the car, the same air-pressure continues in the flexible tube between the cut-off valve and the coupling, and the same 45 air-pressure is exerted upon the parts of the coupling as before the cut-off valve was closed. Consequently the two parts of the coupling which have to be turned upon each other to 50 effect the uncoupling must be moved under this pressure.

The operation of uncoupling under such conditions often requires more time than can well be spared. Considerable force must also frequently be applied before the coupling parts

can be slipped upon each other and opened 55 apart.

To remove the objection last named, and not only enable the operation of uncoupling to be easily and rapidly accomplished, but also to provide means by which the brakes of 60 a car can be set in the event of its cut-off valve becoming accidentally closed, is the aim of the present improvement, which consists as follows:

A A' represent the main air-tubes of an atmospheric air-brake—such as the Westinghouse—which are extended beneath the body 65 of the car.

B B' respectively represent the flexible tubes, which extend outwardly from the main tubes 70 A A', respectively.

C represents the coupling used to connect the tubes B B', and D D' represent the cut-off valves inserted between the tubes A and B and the tubes A' and B', respectively. All these parts 75 are of the customary form, saving the cut-off valves D D'. The plug d of this valve has a small perforation, d², extending transversely through one side, d², of it, so as to form a passage through which air, when the valve 80 is closed, can escape from the flexible tube B into the usual cross opening, d³, in the center of the plug, and the shell d⁴ of the valve also has a small perforation, d⁵, through which air, when the valve is closed, can pass from 85 the space d⁶ to the outer air. At the same time the escape of the air from the main tube A is cut off. This position is shown in Fig. 4. When the valve is opened, as shown in Fig. 3, it will be seen that the passages d² d⁵ 90 are closed. The result is, that whenever the cut-off valves D D' are closed the air remaining in the flexible tubes is exhausted therefrom through the passages d² d³ d⁵ in the valves D D', respectively, to the outer air, and the 95 equilibrium is established upon both sides of the coupling, whereupon the uncoupling can be effected rapidly and easily.

I claim—

The tubes A A', the flexible tubes B B', 100 the coupling C, and the cut-off valves D D', having the passages d² d⁵, combined and operated substantially as described.

WILLIAM O'HERIN.
